UNITED STATES PATENT OFFICE.

FRANK D. FARNAM, OF EDISON PARK, CHICAGO, ILLINOIS, ASSIGNOR TO FARNAM FOUNTAIN CLEANING BRUSH COMPANY, OF CHICAGO, ILLINOIS, A CORPORATION OF ILLINOIS.

CLEANING DEVICE.

1,203,512.

Specification of Letters Patent.

Patented Oct. 31, 1916.

Application filed August 17, 1914, Serial No. 857,024. Renewed March 30, 1916. Serial No. 87,857.

To all whom it may concern:

Be it known that I, FRANK D. FARNAM, a citizen of the United States, and a resident of Edison Park, Chicago, in the county of Cook and State of Illinois, have invented certain new and useful Improvements in Cleaning Devices; and I do hereby declare that the following is a full, clear, and exact description of the same, reference being had to the accompanying drawings, and to the numerals of reference marked thereon, which form a part of this specification.

This invention relates to that class of cleaning devices set forth in my prior application for patent for "Cleaning devices for utilizing volatile liquids", filed on the 15th day of November, 1912, Serial No. 731,591, and wherein a volatile cleaning fluid is discharged from a container by pressure generated therein by the volatilization of said liquid from the heat of the hand holding the container.

The object of this invention is to provide a device for dispensing a cleaning (or other) liquid therefrom in graduated amounts and as required for service, and to afford a construction adapted for use either for volatile or non-volatile liquids and so constructed as to permit the entire contents of the container to be discharged, as required, either through pressure generated by the expansion of the liquid or independently of such pressure, dependent upon the character of the liquid used.

It is also an object of the invention to afford a construction adapted for use in connection with a device such as set forth in my aforesaid pending application for patent wherein the liquid may be discharged by pressure from the volatilization of the liquid or by atmospheric pressure, as required, thus enabling the entire contents of the container to be discharged at the rate required for use.

It is finally an object of the invention to afford a fountain brush, the discharge from the fount of which is occasioned wholly or in part from the heat of the hand or may be produced mechanically, as preferred.

The invention (in a preferred form) is illustrated in the accompanying drawings and herein after more fully described.

In the drawings: Figure 1 is a side elevation of a device embodying my invention.

Fig. 2 is an enlarged, central fragmentary section thereof. Fig. 3 is a section on line 3—3 of Fig. 1. Fig. 4 is a reduced section on line 4—4 of Fig. 2. Fig. 5 is a reduced section on line 5—5 of Fig. 2. Fig. 6 is a reduced fragmentary detail section taken on line 6—6 of Fig. 5.

As shown in the drawings: 1, indicates a container preferably of thin metal, having high thermal conductivity, for example, thin brass or copper, as shown cylindric in form (though not necessarily so) and having a head 2, provided with peripheral flange 3, which fits within the lower or discharge end of the container and is permanently and rigidly secured therein to afford a tight joint and affording a cavity or recess at the bottom of the device to receive the brush back 4, as shown in Fig. 2. Preferably, the end of the container and the flange 3, of said bottom head, are provided on opposite sides thereof with apertures to receive pins or dowels 5, therein, which extend therethrough and into the back of the brush at its periphery, as indicated in Figs. 2 and 4, to removably engage the brush in place. A spring clip 6, of any suitable metal, engages around the lower end of the container and covers the outer ends of said pins or dowels 5, and retains the same in place, but removal of the clip permits the dowels to be removed, thereby permitting the removal of the brush.

A flanged cover 7, tightly closes the upper end of the container and may be applied in place either with or without a gasket, as preferred, and the flange thereof, as shown in Fig. 1, is provided with lamp socket notches on opposite sides thereof to receive therein each a pin 8, set in the upper end of the container and set to extend outwardly from the periphery of the container, as shown in Fig. 1, whereby the cover or cap may be turned into rigid engagement to close the upper end of the container or may be quickly removed therefrom, as preferred.

As shown, an air inlet valve 9, of any preferred construction, may be provided at the inner side of the cap or cover 7 and the closure 10, therefor is supported by a weak spring 11, sufficient normally to hold the closure seated and preventing escape of the contents of the container against any internal pressure, but readily yielding to permit

inflow of air at atmospheric pressure, venting the container thereby to permit discharge of the contents at the bottom. A discharge aperture and short pipe 12, are 5 provided in the bottom head of the container, as shown in Fig. 2, to conduct the liquid through the back of the brush and to the hair (or other) brush material secured thereon, and as shown, a bracket 13, is secured 10 on the inner side of said bottom head and apertured in alignment with said pipe 12, and extending therethrough is a valve stem 14, which, at its lower end, is provided with a tapered valve closure 15, affording 15 substantially a needle valve. Above said closure a collar or enlargement 16, is provided on the valve stem, and a spring 17 is secured on said stem and bears on the collar and said bracket and acts normally to hold 20 the valve seated. Extending diametrically across said container near the top thereof, and secured to its side walls, is a bar 18, and pivotally engaged thereon is a bent lever 19, one arm of which extends above and parallel 25 with said bar 18, and upon which engages the upper hooked end 20, of the valve stem 14. As shown in Fig. 2, a portion of the wall of the container is cut away, and a thin resilient plate 22 is secured thereto in any 30 suitable manner to cover said cut away portion. The other end 21 of said lever 19 extends downwardly and laterally bearing at its free end against said plate 22. If preferred, of course, the wall or shell of the 35 container may be made sufficiently thin to be yieldable and resilient, in which case the entire body portion of the container may be made in one piece.

The operation is as follows: The container is filled to a sufficient extent with the liquid to be dispensed therefrom, by removing the cover 7, to permit of pouring the liquid thereinto and the cover is then replaced, as shown in Fig. 2. A slight pressure is then brought to bear upon the weakened portion of the wall of the container, pressing the arm 21, of the bent lever inwardly and thereby unseating the valve closure 15, and permitting the desired amount 45 of the liquid content to be discharged to the brush through the pipe 12. Such discharge in the case of volatile liquids, is materially assisted by the volatilization of a portion of the contents because of the heat 50 of the hand in which the container is held. Immediately upon releasing the pressure upon the weakened portion of the wall, the valve closes and no further escape of the contents can be effected until the valve is 55 again opened, as before described.

Obviously the arrangement of valve is such that augmentation of pressure within the container, acts normally to hold the valve seated so that under any conditions, 60 when the device is not in use, there can be

no escape of the volatile liquids, for example, gasoline therefrom, and in consequence, danger of fire is obviated. After a considerable quantity of the liquid has been dispensed from the container, and the level thereof falls sufficiently low, the volatilization from 70 the heat of the hand, although present, is much less in extent than when a greater quantity of gasoline or other volatile liquid is in the container. When the valve is open, therefore, atmospheric pressure may assist 75 insuring the discharge by the opening of the valve 10, and the resulting inflow of atmospheric air. Of course, if desired, an automatically acting discharge valve may also be provided in the bottom head 2, of the device, so that the device operates automatically from the heat generated by the hand, as described in my said co-pending application. Where this construction is used, the 80 valve 15, need not be operated until such time as the flow of the hydro-carbon liquid has practically ceased, because of pressure exhaustion, due to the small quantity of 85 gasoline remaining in the container.

Obviously, by the construction described, the discharge of the fluid is at all times in control of the operator, and the quantity may be regulated to his actual needs without failure of the supply nor the excess delivery of the liquid therethrough. As the liquid comes upon the brush, such brush 90 dampened thereby, may be used for cleaning garments or surfaces, as, for example, the cleaning of electrotypes or any other surface requiring such action, and the device may be used continuously until the charge 95 is exhausted, the discharge being at all times perfectly regulated to the will of the operator. Of course, where non-volatile liquids 100 are used, or in other words, those with which the heat of the hand would not be sufficient to generate material or sufficient pressure to assist in the discharge, the discharge may at all times be effected and controlled by means of the actuation of the lever aforesaid through pressure exerted upon the weakened wall 22, of the container, the liquid as discharged being replaced by atmospheric air being permitted to flow in through the 110 valve 10.

Of course, details of construction may be varied through a wide range and I therefore do not purpose limiting the patent granted otherwise than necessitated by the prior art. 115

I claim as my invention:

A device of the class described, comprising a container, a peripherally flanged head in one end of said container, a brush fitted into the recess afforded in said head by said flange, said head having a passage therethrough for supplying fluid from said container to said brush, dowels disposed in registering apertures in said container, flange and brush to retain said parts to- 125 130

gether, a spring clip on said container over-
lying said dowels removably to retain them
in position, a valve controlling the passage
through said head, and lever mechanism
5 within said container operated by pressure
to open said valve.

In testimony whereof I have hereunto

subscribed my name in the presence of two
subscribing witnesses.

FRANK D. FARNAM.
